UNITED STATES PATENT OFFICE.

EARL A. HASTINGS, OF QUIMBY, VIRGINIA.

SPARK PLUG.

Application filed March 7, 1923. Serial No. 623,509.

To all whom it may concern:

Be it known that I, EARL A. HASTINGS, a citizen of the United States, residing at Quimby, in the county of Accomac and State of Virginia, have invented certain new and useful Improvements in a Spark Plug, of which the following is a specification.

The primary object of the present invention is to provide an improved spark plug, so constructed, that the same will operate efficiently under all conditions and not become clogged up or corroded.

Another object of the invention is to provide a spark plug having a novel central electrode, which through its peculiar formation insures a hot big spark for firing the charge and prevents the forming of carbon deposits thereon.

A further object of the invention is to provide an improved central electrode for spark plugs embodying the usual conducting wire, which is coated with an alloy of platinum and mercury and then tightly wound with copper wire, and finally provided with a plastic coating of an alloy of mercury, zinc, lead and tin, the copper wire serving as a good conductor for heat for insuring the heating of the wire, and the plastic coating of the alloy of mercury, zinc, lead and tin, which serves to intensify the spark by heating the wire.

A still further object of the invention is to provide an improved spark plug of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a side elevation of the improved central electrode for spark plugs showing the outer coating therefor in section.

Figure 2 is a transverse section through the improved electrode taken on the line 2-2 of Figure 1.

Figure 3 is a similar section taken on the line 3-3 of Figure 1, and

Figure 4 is an enlarged fragmentary detail longitudinal section through the lower

end of the electrode showing the construction thereof.

Referring to the drawings in detail, wherein similar reference characters designate corresponding parts throughout the several views the letter A generally indicates the improved electrode, which is sealed within an ordinary body of insulation or porcelain and the porcelain is then secured to steel jacket of the spark plug in the ordinary manner.

This electrode A embodies a central metal rod 5 or wire of the desired gage. The rod or wire 5 is of course formed of good electric conducting material and has the upper end thereof threaded as at 6, for the reception of a retaining nut and washer 7 and 8, it being obvious that the nut and washer is utilized for holding the central electrode in place on the porcelain body when the electrode is associated therewith.

It is preferred to coat the electrode 5 with an alloy consisting of platinum and mercury.

After the rod 5 is coated, a thin copper wire is wound tightly around the same as at 9, and it can be seen by referring to Figure 1 of the drawings that the windings increase from the opposite ends of the rod toward a point near the lower end of the rod. At the point where the windings increase and meet, the wire is wound to form a stop shoulder 10 for engaging the lower end of the porcelain.

The portion of the windings 9 above the shoulder 10 is then coated with an alloy of platinum, mercury, lead, tin and zinc 12 for a purpose, which will be hereinafter more fully described. These metals are combined together in any preferred method and are of a plastic consistency, which can be readily spread on the copper windings by the fingers.

If so desired a suitable sleeve or ferrule 11 can be slipped on the lower end of the rod 5 and secured thereto in any preferred manner, so as to prevent copper wire from becoming unwound and from slipping off of the lower end of the rod. This of course is not vital to the invention. It is also preferred to solder the nut 7 on the rod 5, as at 12, which also aids in the intensifying of the spark.

The mercury in the alloy serves as a vehicle for the other metals and when the other metals are added thereto the alloy assumes

a semi-liquid or pasty form, which as stated can be readily spread on the copper coil. The platinum resists the electrical current which also causes the electrode to heat. The 5 lead helps to fuse the alloy. The tin being a good conductor of electricity and also having a low boiling point also helps to keep the alloy in a semi-liquid or paste form upon cooling. The zinc also helps to heat 10 the electrode, which helps to fire the charge. The lower winding of the copper on the rod 5 acts in the nature of a heater or accumulator, and it is obvious that as copper is a good conductor of heat, the same will 15 store up the heat and tend to heat the rod. The electrode will, under all conditions, burn itself free of any oil, grease or carbon and will not short circuit even when water is poured on a plug. 20 Changes in details may be made without departing from the spirit or the scope of this invention.

What I claim is:—

1. A central electrode for spark plugs com-

prising a rod of conducting material, a copper wire coiled about the rod, a plastic alloy of mercury, zinc, lead and tin placed on the copper wire starting at a point above the lower end thereof, the portion of the wire with the alloy being adapted to be embedded 25 in the porcelain body of the spark plug. 30

2. A central electrode for spark plugs comprising a wire coated with platinum and mercury, a copper wire coiled about said coated rod, and a plastic coating of mercury, 35 zinc, and lead placed upon the wire and terminating short of the upper and lower ends thereof, the copper wire being wound a greater number of turns about the rod adjacent to the lower end thereof to form a 40 stop shoulder.

In testimony whereof I affix my signature in presence of two witnesses.

EARL A. HASTINGS.

Witnesses:

W. L. GLADDEN,
P. C. AYRES.
